UNITED STATES PATENT OFFICE.

EDWIN F. PORTER, OF BOSTON, MASSACHUSETTS, ASSIGNOR TO BENJAMIN F. PEACH,
TRUSTEE, OF LYNN, MASSACHUSETTS.

ELECTRIC HEATER.

No. 889,040.

Specification of Letters Patent.

Patented May 26, 1908.

Application filed January 29, 1906. Serial No. 298,347.

To all whom it may concern:

Be it known that I, EDWIN F. PORTER, of Dorchester, Boston, in the county of Suffolk and State of Massachusetts, have invented 5 certain new and useful Improvements in Electric Heaters, of which the following is a specification.

My invention relates to improvements in electric heaters especially to such heaters as 10 are used in electric-cars.

The object of my invention is to obtain a thorough and perfect diffusion of heat throughout the entire area of the car.

A further object is to effect the ventilation 15 of the car by taking in fresh air from out of doors over the heat generating resistances.

Another object is to properly suspend the 20 resistance wires in the heater. In this construction a considerable saving of current is realized and greater mechanical and electrical efficiency as well as permanency of construction are insured.

In the accompanying drawings which illustrate a construction embodying my invention, Figure 1 is a perspective view of a seat in an electric car showing the heater running the full length of the heel-board at its lower edge. Fig. 2 is a transverse section of the seat and heater showing the manner in which 25 fresh air is taken in through an opening in the floor. Fig. 3 is a section of the heater proper illustrating the method of suspending the heater coil. Fig. 4 is a back view showing the same construction. Fig. 5 is a trans- 30 verse section through one of the supporting posts which suspend the coil. Fig. 6 is a modification of the construction shown in the cross section Fig. 2, the difference being 35 the location of the fresh-air in-take. Fig. 7 is a perspective view of the entire seat of the car showing the floor in section for the purpose of displaying two fresh air in-takes supplemented by L-shaped pipe. Fig. 8 is a 40 transverse section partly through one of the pipes shown in Fig. 7 and showing more clearly the air circulation. Fig. 9 is a representation of one of the in-take pipes showing the manner in which it is closed with a valve, the valve being shown open. Fig. 10 shows 45 the assembling of the heater, the resistance coils being made in sections and insulated one section from the other on an insulating support.

Like letters of reference refer to like parts throughout the several views.

In Fig. 1, A is the car seat having a heel board B at the lower part of which is located the heater casing C made in sections D, E, F, G, H, I, J and K. These sections are hinged to the heel board at their upper edge, just below which is a grille work L for the purpose of allowing warm air to enter the car. In the front of the heater are dampers C' for the purpose of regulating the flow of air from the car into the heater. These dampers are shown 60 open in the sections D, F and K and closed in the remaining sections.

In the cross section, Fig. 2, C is the casing of the heater hinged at M. L is the grille work for admitting warm air unto the car. 70 P is the heater coil supported by the posts Q (Fig. 3) which in turn are supported by the bar R from which they are insulated by the insulating washers S and S' and the insulating bushing T which fills the hole U. This 75 hole is countersunk at V and v' (Fig. 5).

The bar R (Fig. 4) is provided with an arm W for the purpose of attaching it to the heel board, B and between the arm and the heel board is a sheet of asbestos paper X as shown 80 in Fig. 2.

As shown in Fig. 5, the resistance coil P enters the slot Y in the post Q which slot is adapted to be pinched together or riveted over for the purpose of holding the coil in 85 place. The post Q passes through the hole U and is riveted over a washer Z which holds the post in place. The hole A' is shown in the floor of the car in Fig. 2 for the purpose of admitting fresh air to the heater. 90

In Fig. 6, the hole in the floor of the car is shown at A² and a slot A³ conveys the fresh air admitted by the hole A² to the heater.

In Fig. 7, B' and B² are L-shaped pipes for the purpose of accelerating the circulation of 95 air through the hole A² Fig. 6.

In Fig. 8, the L-shaped pipe B³ is shown partly in section and in Fig. 9, D' is a valve for closing the hole A². This valve is shown open in Fig. 9 and is shown closed in dotted 100 lines Fig. 7; a similar valve B³ for the pipe B' is shown open in Fig. 7 with the car traveling in the direction indicated by the arrow O'.

The operation is as follows: The heat is diffused throughout the entire length of the 105 car by means of the heating coil which

extends throughout; fresh air coming in through the holes A' in the floor of the car passes over the heating coils P and out through the grille work L into the car thereby giving perfect ventilation as well as the same degree of heat from one end of the car to the other. If it is desired to take in some of the heated air from the car, the dampers C' may be opened, the heater then drawing part of its air from inside the car and reheating it while supplying partly fresh air through the holes in the bottom of the car. It will be seen that by proper use of these dampers, the heating and ventilation may be modified and regulated at the will of the operator.

The casing of the heater being made in sections is a convenience in manufacture and being hinged makes access to the heater convenient.

20 The holes in the bottom of the car may be placed directly under the heater as shown at A' in Fig. 2, or more remote under the seat, as shown at A², Fig. 6, in which latter case the slot A³ is provided for conveying fresh air to the heater. For the purpose of accelerating the circulation of air through holes in the bottom of the car, the L-shaped tubes B' and B² are provided, having valves B³ and D' which close over the holes in the bottom of 25 the car. This opening of the valve B³ and closing of the valve D' is due to the car moving in the direction of the arrow O', the closing of the valve D' preventing taking the air out again which enters at B' due to the motion of the car as well as to the convection of the heater coil; the operation would be reversed if the car were traveling in the opposite direction.

In Fig. 10, P', P² and P³ represent three 40 sections of the heater coil insulated from each other on the insulating wall F'.

Attention is called to the manner in which the heat resistance coil is suspended; it is common in the construction of electric heaters to wind the coil on an insulating support or to suspend it on an insulating bar thereby in both cases interfering with the circulation of air through the heater, causing overheating and frequently actual burning out. In 45 my construction, it will be seen that the heater is strongly supported by metallic posts which are insulated by mica washers S and S' on a strong metallic bar R,—the heating coil being freely suspended in the air 50 without contact other than with the metallic posts Q. This construction allows the air to freely circulate around every part of the heating coil producing a uniform temperature cooling the coil to a safe degree of heat 55 in every part, thereby making the heater operative, strong and durable.

Having thus described the nature of my invention and set forth a construction embodying the same, what I claim as new and

desire to secure by Letters Patent of the 65 United States is:

1. In an apparatus of the character described, one or more heat generating electric conductors forming an electric heater, a stud or hanger adapted to engage or grip one or 70 more coils of said heater, a support adapted to support said hanger, and means for insulating said hanger from said support.

2. In an apparatus of the character described, one or more heat generating electric 75 conductors forming an electric heater, one or more studs or hangers each adapted to engage or grip one or more coils of each of said conductors, a separate insulated support adapted to support the studs or hangers 80 engaging each conductor, and means for insulating said hangers from said supports.

3. In a vehicle, a seat, a heel board for said seat, an electric heater located at the lower part of said heel board and outside of same, a 85 casing covering said heater, grille work at the top of said casing, openings in the bottom of said casing to admit air thereto from said vehicle, and ducts from the floor of said vehicle to admit outside air to said heater.

4. In a vehicle, a seat, a heel board for said seat, an electric heater located at the lower part of said heel board and outside of same, a 90 casing covering said heater, grille work at the top of said casing, openings in the bottom of 95 said casing to admit air thereto from said vehicle, ducts from the floor of said vehicle to admit outside air to said heater, and means for controlling the passage of air through said openings.

5. In a vehicle, a seat, a heel board to said seat, an electric heater in combination with said heel board, and means for admitting air to the back of said heater and for venting the heat from the front of said heater.

6. In an apparatus of the character described, one or more heat generating conductors forming an electric heater and extending the length of the car, a series of supports for suspending said heater and insulated from each other, and means for connecting said heater and said supports and insulated from said supports.

7. In an apparatus of the character described, one or more heat generating conductors forming an electric heater and extending the length of the car, one or more supports for suspending said heater, and means for connecting said heater and said support or supports and insulated from said support or 115 supports.

8. In an apparatus of the character described, one or more heat generating conductors forming an electric heater, means for supporting and insulating said heater, and a 120 casing covering said heater and made in sections to allow access thereto.

9. In an apparatus of the character de-

scribed, one or more heat generating conductors forming an electric heater, means for supporting and insulating said heater, and a casing covering said heater and made in pivoted sections to allow access thereto.

5 In testimony whereof, I have signed my name to this specification in the presence of

two subscribing witnesses, this 25th day of January, A. D. 1906.

EDWIN F. PORTER.
